United States Patent Office.

DAVID D. HANSON, OF WEARE, NEW HAMPSHIRE.

Letters Patent No. 105,449, dated July 19, 1870.

IMPROVEMENT IN ELEVATOR.

The Schedule referred to in these Letters Patent and making part of the same.

To all whom it may concern:

Be it known that I, DAVID D. HANSON, of Weare, in the county of Hillsborough and State of New Hampshire, have invented a new and useful Improvement in Elevators, or machines for raising heavy weights; and I do hereby declare that the following is a full and exact description thereof, reference being had to the accompanying drawing and to the letters of reference thereon.

My invention consists in a novel construction and arrangement of elevators for raising heavy weights.

In the accompanying drawing—

Figure 1 is a front view of my improved stump-puller.

Figure 2 is a side view of the same.

In the construction of my elevator, a suitable frame, I, is made, or the working parts of the machine may be mounted on an axle provided with wheels, for moving the machine as desired.

The shaft A, upon which the chain is wound, has at one end a screw-thread, and is provided with a nut, so that the shaft will travel endwise when it is rotated, thus keeping the line of draft in the same perpendicular line, while the chain is prevented from winding upon itself.

Attached to the chain are double-jointed hooks or grapples H, for seizing the log, stone, rail-track, or other objects.

The shaft carries a ratchet-wheel, B, which is turned, with the shaft, by means of the lever C and pawl D; and the dog G holds the ratchet and shaft while the lever is raised to take a new hold.

The pawl D is released from the ratchet-wheel by means of a rod, D', and short lever L, and the dog is released by means of an elbow-lever, E, which bears upon spring F when rotated, thus lifting the dog and allowing the chain to unwind.

Having thus fully described my invention,

I claim—

The above-described elevator, provided with the shaft A, having end play, and operated by the lever C, ratchet B, pawl D, rod D', and lever L, combined and operated substantially in the manner and for the purposes set forth.

DAVID D. HANSON.
